UNITED STATES PATENT OFFICE.

HARRY B. LOCKWOOD AND GEORGE W. BRINKMAN, OF CHICAGO, ILLINOIS.

ELEVATOR-CONTROLLER INTERLOCK.

1,276,088.

Specification of Letters Patent. Patented Aug. 20, 1918.

Application filed May 13, 1918. Serial No. 234,320.

To all whom it may concern:

Be it known that we, HARRY B. Lockwood and GEORGE W. BRINKMAN, citizens of the United States of America, and residents of 5 Chicago, county of Cook, and State of Illinois, have invented certain new and useful Improvements in Elevator-Controller Interlocks, of which the following is a specification.

10 This invention relates to that general class of safety appliances for elevators whereby the elevator shaft doors cannot be opened unless the controller arm is in the neutral or off position, and likewise it is 15 necessary to close the door before the controller arm can be moved away from such neutral position.

The purposes of this invention are to provide a simplified construction of interlock of this nature which may be applied practicably to an electric controller of known construction and widely in use in connection with passenger elevators in office buildings; and to provide an interlock for 25 attachment to the type of controller shown in the drawings which may be applied without material change in the controller or necessitating changing its location in the car, disturbing its mounting, or, as is 30 sometimes done, cutting an aperture through the wall of the car adjacent to the rear of the controller.

An illustrative embodiment of the invention is shown in the accompanying drawings, in which—

Figure 1 is a front view of an electric controller provided with the present improvements and with the front cover plate removed.

40 Fig. 2 shows the controller in side elevation, but with the casing and cover plate in section.

The results of this invention in one instance have heretofore been accomplished by 45 attaching a segment to the rear face of the controlling arm, said segment having a peripheral apertured flange which interlocks with a reciprocating rod under the control of the door lock operating mechanism. Since 50 the controllers were generally mounted against one wall of the car, such construction necessitated moving the controller inwardly from said wall to provide space for the segment, or otherwise cutting an aperture in the wall of the car within which the segment could rotate. With the present

construction, no change in the mounting of the controller is necessary, nor is it necessary to make a cut in the wall of the car. The device is so designed as to fit within 60 the lower front part of the controller casing without change in the latter or change in the operating devices of the controller.

The drawings show a well-known type of electric controller comprising a casing 1 having outlets 2 and 3 for electric conduits and a front cover plate 4 screwed to the casing 1. The circuit controlling devices mounted within the casing 1 do not form a part of the present invention and are illustrated herein only to the extent necessary to show how movement is imparted to the interlocking plate 5 which is the specific construction provided by the present invention.

75 The controller handle 6 is carried by an arm 7 pivotally mounted in a bearing 8 cast in the casing 1. The pivotal connection between the bearing 8 and arm 7 is represented by a short headed shaft 9. A forked extension 10 projects downwardly from the arm 7 and, through the plate 5 and a pair of links 17 and 18, co-operates with a centering spring 12 compressible in two directions along the guide rod 13 projecting inwardly 80 from the sides of the casing. The outer ends of the spring 12 bear against the adjustable members 15 slidably mounted on the rod 13 and connected to the forked end 16 of the arm 10 by links 17 and 18 85 and the plate 5. The forked end 16 of the arm 10 has stub shafts 19 and 20 passing through apertures in the inner ends of the links and a vertical slot 21 in the center of the plate 5. The links are provided with 90 longitudinal slots 22, and the plate 5 also has longitudinal slots 23 through which project trunnions or stub shafts 24 on collars 25 movable with the members 15. The links 17 and 18 and the plate 5 are retained on the 95 stub shafts 19, 20, and 24 by washers 26 and cotter pins 27. Due to the connection at the vertical slot 21 between the plate 5 and the trunnion 19 on the arm 10, the plate is caused to reciprocate with the arm when the 100 arm is oscillated around the shaft 9. The spring 12 is accordingly compressed one way or the other, depending upon the direction of movement of the arm 10, and serves to restore this arm and the arm 7 rigid therewith to central position upon the release of 110 the operating handle 6. The plate 5 in this

respect accordingly has the same function as the links 18 and 19, and in fact replaces a pair of said links. The plate 5 is guided during its reciprocating motion by a guide bar 28 fixed to cover plate 4 and a guide bar 29 fixed to the casing 1 by screws 30. A horizontal flange 31 on the lower edge of plate 5 is provided with an aperture 32 which registers with a reciprocating rod 33 when the plate is in its central position as shown, and the operating handle 6 is in the off or neutral position. The rod 33 is movable with the door lock operating pedal which projects upwardly through the floor of the car as well known (not shown in the present drawings). The rod 33 must move upwardly when one of the shaft doors is unlocked by the depression of said pedal. Such upward movement is possible only when the controlling arm is in the off position, since at that time, the aperture 32 registers with the rod 33. At all other positions of the controlling arm and plate 5 movable therewith, the flange 31 prevents upward movement of rod 33 and the depression of the controlling pedal. The function of the guide bars 28 and 29 is to positively prevent any rocking of the plate 5 or lost motion therein if the rod 33 is projected against the lower edge of the flange 31. Any upward movement of the rod (and coincidental movement of the door unlocking mechanism) is thereby practically prevented until the control lever is in neutral position.

Although but one specific embodiment of this invention has been herein shown and described, it will be understood that numerous details of the construction shown may be altered or omitted without departing from the spirit of this invention as defined by the following claims.

We claim:

1. An electric controller of the class described, comprising a casing having a controller arm journaled therein, a plate mounted within the lower part of said casing and having a slot and pin connection to said arm whereby said plate is reciprocated upon oscillating motions of the arm, an

aperture in said plate, and a movable rod forming part of the door lock operating mechanism in position to be projected through said aperture when the controlling arm is in its neutral or off position. 55

2. An electric controller of the class described, comprising a casing having a controller arm journaled therein, a plate mounted within the lower part of said casing and having a slot and pin connection to said arm whereby said plate is reciprocated upon oscillating motions of the arm, said plate having a horizontal flange provided with an aperture, and a movable rod forming part of the door lock operating mechanism in position to be projected through said aperture when the controlling arm is in its neutral or off position. 65

3. An electric controller of the class described, comprising a casing having a controller arm journaled therein, a plate mounted within the lower part of said casing and having a slot and pin connection to said arm whereby said plate is reciprocated upon oscillating motions of the arm, an aperture in said plate, a movable rod forming part of the door lock operating mechanism in position to be projected through said aperture when the controlling arm is in its neutral or off position, and spring 80 centering devices for said arm arranged to be actuated by the movement of the plate. 70

4. An electric controller of the class described, comprising a casing having a controller arm journaled therein, a plate mounted within the lower part of said casing and having a slot and pin connection to said arm whereby said plate is reciprocated upon oscillating motions of the arm, an aperture in said plate, a movable rod forming part of the door lock operating mechanism in position to be projected through said aperture when the controlling arm is in its neutral or off position, and guides for said plate arranged to prevent any but 95 straight reciprocating motion of the plate. 90

Signed at Chicago this 6th day of May, 1918.

HARRY B. LOCKWOOD.
GEORGE BRINKMAN.
